UNITED STATES PATENT OFFICE.

GEORGE GOODLINE, OF PATERSON, NEW JERSEY, ASSIGNOR TO BENJAMIN EASTWOOD, OF SAME PLACE.

SHUTTLE-BOX-OPERATING MECHANISM FOR LOOMS.

SPECIFICATION forming part of Letters Patent No. 498,260, dated May 30, 1893.

Application filed June 7, 1892. Serial No. 435,796. (No model.)

To all whom it may concern:

Be it known that I, GEORGE GOODLINE, a citizen of the United States, residing in the city of Paterson, in the county of Passaic and State of New Jersey, have invented a new and useful Improvement in Shuttle-Box-Operating Mechanism for Looms, whereby the operation of changing by raising and lowering the boxes containing shuttles with quills of different shades and colors used in the operation of weaving textile fabrics may be more readily and accurately performed than hitherto, of which the following is a specification.

It may be understood that in the operation of weaving a fabric with a figured design, many different colors or shades and tints may be required to form the pattern as in flowers, fruit, leaves, &c., which are supplied by different shuttles having quills wound with such different colors or shades. These shuttles are held usually in separate compartments formed in a vertically movable box, which are brought alternatively in line with the race formed on the batten to permit the picking stick to throw such shuttle from the box on the opposite side passing through the warp shed in its progress or travel. The one shuttle may remain in operation passing backward and forward for several picks or movements of the batten, and then be replaced by another which may be located in a compartment above or below it, in which event the box is raised or lowered, removing the one and replacing it with another. In some cases the design may call for a shuttle which may be separated from the one in use by one containing a color not required. In this case the box has to be lifted or lowered two spaces or compartments, passing by the one not required, or as in the case of a box containing four shuttles the top shuttle may be in use and the bottom one called for, then the box will have to be raised the whole distance of the travel. It will be understood that the boxes at each end of the batten are connected by suitable levers and arranged so that they alternatively serve as receiving or discharging receptacles for the shuttle in use.

My invention relates to the mechanism of the loom in connection with the Jacquard machine performing the duty of so operating

the shuttles with such a degree of accuracy and certainty, that the operation of weaving may be performed more rapidly and perfectly than it hitherto has been done; the operation of raising and lowering the boxes without shock or excessive vibration being of considerable importance when the delicate texture of silk as a filling is taken into account.

Another advantage is obvious in the facility with which the mechanism lifting the boxes may be made to enter into engagement with the driving mechanism, thereby relieving the cords and connecting wires from undue strain and wear.

The invention consists in the details of construction and in the arrangement and combination of parts, hereinafter more fully described and claimed.

Referring to the accompanying drawings, in which like letters and numerals of reference indicate corresponding parts in each of the several views: Figure 1 is a side elevation of a loom, embodying my improvements, only those parts of the loom being shown, which are necessary to fully illustrate the nature and operation of my invention. Fig. 2 is an enlarged view in elevation of the pattern mechanism and its connections. Fig. 3 is a top plan view of the parts shown in Fig. 2. Fig. 4 is an enlarged detail view of the master gear wheel, its co-operating mutilated crank gears and their connecting levers (the same being a rear view looking in the direction of the arrow in Fig. 7.) Fig. 5 is a diagram, showing the movements of the shuttle box operating levers. Fig. 6 is an enlarged sectional view on the line $y-y'$ of Fig. 1. Fig. 7 is an enlarged sectional view on the line x of Fig. 1. Fig. 8 is a similar sectional view taken on the line $z-z'$ of Fig. 1. Fig. 9 is a detail sectional view on line y of Fig. 7.

In said drawings a represents the frame of a loom, in which is arranged the shaft c , adapted to transmit its motion through crank 50 and pitman r to the lay or batten t secured to swords t' , the latter fulcrumed at z to the frame. At each end of the lay are arranged the shuttle boxes u supported by rods v and surrounded by spiral springs w , as in the usual manner. On the shaft c is also secured a cam d adapted to operate one arm of angle

lever e , which latter is pivotally secured to the frame, as shown at f , and which is held against cam d by spring 37 as shown in Fig. 1. The other arm of said lever is provided 5 with an elongated slot, in which is pivoted (adjustably) on a pin e^2 one end of link g . The free end of said link is pivoted to radial lever p^3 , carrying pawl p^4 , which latter is adapted to operate the ratchet wheel p^2 , secured to shaft n , on which is mounted the radial lever p^3 . Said shaft has its bearings in frame a and also in a bracket frame m , as clearly shown in Figs. 1, 2 and 3 of the drawings. The link g is also provided with a pin 10 h , adapted to be engaged by the hook i , pivoted at j to frame a , and operated through cord k from the Jacquard machine in the ordinary manner.

On shaft n is firmly secured a sprocket 20 wheel o , upon which the pattern chain, provided with wheels or rollers p , is located. An octagonal stop wheel p^4 is also secured to said shaft, and is controlled by a stop pawl or spring p^5 , the latter being secured to frame a 25 in any desired manner.

Secured in bearings in the upper part of the frame m is an eccentric shaft n' , upon which are fulcrumed four treadle levers q, q', q^2, q^3 , only two being shown in Figs. 1 and 2. To 30 the outer end of said shaft n' is firmly secured a hand or operating lever p^6 , by means of which the levers q, q', q^2 , and q^3 may be lifted out of engagement with the pattern wheel, when necessary.

35 The free ends of the treadle levers are connected by cords or wires r', r^2, r^3 , and r^4 with the shuttle box operating mechanism, as will be hereinafter more fully described.

To the frame a are secured in any desired 40 manner, bracket frames 1 and 2, the projecting portions $51, 51, 52$, and $52, 52$ of which form the bearings for the shafts 3 and 4, and 5 and 6. On each of these shafts is arranged a mutilated crank gear, 7, 8, 9 and 10 respectively, 45 which is splined thereon by a feather, operating in a groove 34 of each shaft, as clearly shown in Figs. 6 and 9. Each of said crank gears 7, 8, 9 and 10 is provided with an annularly grooved collar 32, the groove of which 50 is engaged by the pins 33, secured to the free ends of the forked portions 31, of levers 35, 36, 37 and 38 (Figs. 7, 8 and 9.) The crank gear 7 on shaft 3 is operated by bell crank lever 35 integral with sleeve s^3 , which latter is 55 loosely arranged on shaft 16. The free end of bell crank lever 35 is connected by cord r^2 with treadle lever q' . The crank gear 8 on shaft 4 is operated through lever 36, depending from sleeve s^2 , which latter is firmly secured 60 to shaft 16. On the opposite end of said shaft is also firmly secured a sleeve s' , provided with an inwardly extending arm 39, the free end of which is attached to the cord r' . The crank gear 9 on the shaft 5, is shifted by 65 means of the bell crank lever 37, pivoted as at 40 to an extending bearing of the bracket frame. The free end of the horizontal arm of

said bell crank lever is provided with a pin, operating in a slot arranged in the free end of lever 41, integral with sleeve s^5 , which latter 70 is loosely arranged on shaft 17. Said lever 41 is operated by cord r^3 . The crank gear 10 on shaft 6 is operated in a similar manner by bell crank lever 38, pivoted at 42 to an extending bearing of the bracket frame. Its free arm 75 is provided with a pin, engaging the slotted end of lever 43 integral with sleeve s^6 , which latter is secured to shaft 17. At the opposite end of said shaft is also secured a sleeve s^4 80 provided with a horizontal arm (similar to arm 39 Fig. 8, to which latter the cord r^4 is attached. To the outer ends of each of the shafts 3, 4, 5 and 6 is secured a hand wheel R , whereby said shafts can be operated by hand when the loom is not in motion. The 85 hereinbefore mentioned shafts 16 and 17 are arranged at right angles to the shafts 3, 4, 5 and 6, and have their bearings in the upwardly extending portions $54, 54$ and $55, 55$ of the bracket frames 1 and 2 respectively. 90 Each of said crank gears 7, 8, 9 and 10 has two diametrically opposite teeth removed, as clearly shown in Figs 1 and 4. These teeth are removed to prevent said crank gears from being rotated by their gear connection more 95 than one-half a revolution at one time.

On the shaft b , which has its bearings in the frame of the loom, is firmly secured the mutilated master gear wheel M , the periphery of which is provided with sets of teeth N and O , 100 arranged in two vertical planes. The teeth N are arranged in two quarter sections, diametrically opposite to each other, the quarter sections of the teeth being separated by a quadrant of plain surface of the wheel. The teeth O are arranged in similar sections, and are placed alternately with the teeth sections N , all as clearly shown in Fig. 1, 4, 6, 7 and 8. The teeth sections N are adapted to operate 105 the crank gears 7 and 8 and the sections O , the crank gears 9 and 10 in the manner hereinafter more fully described.

Upon the shafts 3, 4, 5 and 6 are firmly secured the disks having two diametrically opposite flat faces 18, 19, 20 and 21 respectively. 115 To the flat faced disk 18 is secured a pin or stud 22, arranged eccentrically to shaft 3, and engaging the elongated slot 23 of lever 11, which lever 11 is at about its center also eccentrically pivoted to the shaft 4 as clearly 120 shown in Figs. 4 and 5 of the drawings. The free end of said lever is pivotally connected to the upper end of link 56, the lower end of which link is pivoted to the shuttle box supporting rod v as shown in Fig. 1. To the flat faced 125 disk 20 is secured a pin or stud 24, arranged eccentrically to shaft 5 and engaging the elongated slot 25 of lever 12, which latter at about its center is also eccentrically pivoted to the shaft 6. The free end of said lever is pivotally connected to lever 13, secured to shaft 14. To the opposite end of said shaft is secured a lever 59 (shown in dotted lines in Fig. 1), the free end of which is pivotally con-

ected to the shuttle box supporting rod (on the opposite side of the loom), in a similar manner as is the lever 56 pivoted to its shuttle box supporting rod *v*. The flat faced disks 5 18 and 19 and also 20 and 21 are provided with locking devices or brakes 26 and 27, each of which consists of two angle levers, (pivoted preferably to the bracket frames 1 and 2), one arm of which rests upon the periphery of 10 the disk and the other arm is controlled by a spiral spring 28, connecting with the like arm of the other brake, as shown in Fig. 4.

The motion from the driving shaft *c* is transmitted to the shaft *b*, by a train of gear 15 wheels, arranged on the opposite side of the loom, as in the ordinary manner, and is not illustrated in the drawings.

The operation of the machine is as follows: During the operation of plain weaving, the 20 shuttle box controlling mechanism is not brought into operation, as the hook *i* is in engagement with the pin *h* of lever *q*, thus raising the angle lever *e* out of engagement with the cam *d* on the driving shaft *c*. When the 25 Jacquard chain calls for the introduction of a color to be worked in a figure or design of the fabric, the jack or hook of the machine will draw the cork *k* upward, thus lifting the hook *i* out of engagement with the pin *h*. By the 30 action of spiral spring 37 the angle lever *e* is drawn down into contact with the depressed portion of the cam *d*. This cam *d*, rotating with the shaft *c*, communicates its motion through angle lever *e* and link *g* to 35 the pawl *p'* and ratchet wheel *p*², thus operating the shaft *n*, and rotating it a required distance. The sprocket wheel *o* is thus revolved, operating the pattern chain until one 40 of the rollers *p* thereof comes under and lifts one of the levers *q*, *q'*, *q*², *q*³. The octagonal stop wheel *p*⁴ and its pawl *p*⁵ holds the shaft *n* and thus the sprocket wheel *o* in the above described position. In order to clearly understand the operation of the shuttle box 45 changing device, reference should be had to Figs. 1, 4, 5 and 6; Fig. 4 illustrating the position of lever 11, when the second compartment of the shuttle box, (from the top) is brought opposite the lay or race and is in position to discharge its shuttle, the position of 50 the lever 11 and its operating pin 22 and the eccentric on shaft 4 being indicated in Fig. 5 by the diagram marked II. Supposing that the top shuttle is called for, after the second 55 shuttle (from the top) has performed its operation; the lever *q* is raised by the roller *p* of the pattern chain, thus lifting the lever 39 on collar *s'*, and as said collar is firmly secured to shaft 16, to the other end of which 60 is also firmly secured the sleeve or collar *s*², the lever 36 of the latter is operated, and through its forked projection 31 engaging the grooved collar 32 of crank gear 8, throws said 65 crank gear (by sliding it on its shaft) into engagement with one toothed section *N* of master wheel *M*. The shaft 4 is thus revolved one half revolution or until the teeth section of the mas-

ter gear comes opposite that point of the crank gear at which the tooth has been removed, and as the lever 11 is eccentrically pivoted to 70 said shaft, it is moved upward, using the pin 22 of flat faced disk 18 for its fulcrum into the position shown in the diagrammatic view numbered I. Through the connection of the free end of lever 11 with the shuttle box supporting rod, the latter is lowered one compartment, and thus the corresponding shuttle (the top shuttle) brought into operation. The crank gear cannot be again rotated by the second tooth section of the master gear until 80 it is returned to its normal position by the brake, that is to say, the teeth of the master gear will be opposite the mutilated part of the crank gear until the crank gear is turned to its proper position by the brake. Should said 85 top shuttle be required for more than one pick, the hooked end lever *i* is lowered by the jack lever into engagement with the pin *h* of link *g*, thus withdrawing the angle lever *e* from contact with the cam *d*, and thus preventing a further rotation of the shuttle changing device on shaft *n*. In that case the lever *q* remains in its elevated position, and the teeth of the crank gear 8 in alignment with the teeth of the master gear; but the 90 crank gear is prevented from turning, by that portion of its periphery from which the tooth has been removed coming opposite the teeth of the master gear. By the dropping of the lever *q*, the crank gear 8 is returned to its 95 former position, that is to say, out of engagement with the teeth *N* of the master gear. Now supposing that after the shuttle of the top compartment has performed its function, the shuttle of the third compartment (from 100 the top) is called for. The angle lever *e* is again brought into contact with the cam *d*, in the manner hereinbefore described, and the link *g*, is actuated, operating the pawl and ratchet and thus the sprocket wheel *o*, until 105 one of the rollers *p* comes under and raises the lever *q'*. Through the cord connection *r*², the sleeve *s*³ is rotated, and through the forked portion of the bell crank lever 35 throws the crank gear 7, by sliding it on its shaft 3, into 110 engagement with the toothed section *N* of the master wheel. The flat faced disk 18 on shaft 3 is thus rotated, until its eccentric pin 22 reaches its lowest position, thus moving the lever 11 into the position shown in the diagram 115 numbered III, Fig. 5. Through the connection of the free end of lever 11 with the shuttle box supporting rod, said rod and the box are raised two compartments, and the third shuttle (from the top) is thus brought into operation. 120 Through the dropping of the lever *q'*, the crank gear 7 is drawn out of engagement with the teeth *N* of the master wheel. If said third shuttle (from the top) is required for more than one pick, the shuttle changing device on shaft *n* is suspended in its motion as heretofore described. Now supposing the 125 bottom shuttle is called for: In that case the lever *q* is raised, and through the heretofore

described connection with crank gear 8, said gear is brought into engagement with the teeth N of the master gear, and is thereby rotated, thus raising the lever 11 through its eccentric connecting with shaft 4—one compartment. The pin 22 on flat faced disk 18 remaining in its lowest position and acts as the fulcrum for the lever 11. This position of the lever 11 is indicated by diagram numbered IV Fig. 5. In case the second shuttle (from the top) is required, the crank gear 7 is operated to bring the pin 22 of flat faced disk 18 into its highest position, whereby the lever 11 assumes the position shown in the diagram numbered II of Fig. 5. The spring controlled levers or brakes 26, serve to throw the crank gears 7 and 8 into their normal position, after said gears are withdrawn from alignment with the master gear, as will be manifest. The mode of operation of the lower crank gears 9 and 10 and the connecting lever 12 is the same as that of the upper crank gears 7 and 8 and the lever 11, except that the crank gears 9 and 10 are brought into engagement with the toothed sections O of the master gear, and the lever 12 operates through shaft 14 and lever 39 the shuttle supporting rod on the opposite end of the loom.

Having thus described my invention, what I claim as new, and desire to secure by Letters Patent, is—

1. The combination of the driving shaft c, cam d carried by said shaft, angle lever e, spring 37 for normally holding one arm of said lever in contact with the cam d, and means for holding lever e against the force of the spring, link g adjustably pivoted to the other arm of said lever e, pawl p', ratchet p², and sprocket wheel o carrying the pattern chain, the free end of said link g being adapted to operate said sprocket wheel o through pawl p' and ratchet p², with a series of levers q, q', q², q³, adapted to be operated by said pattern chain, a series of forked levers adapted to be operated by said levers q, q', q², q³, a series of crank gears adapted to be moved on their shafts by said levers q, q', q², q³, through the series of forked levers connected to said levers q, q', q², q³, by cords r', r², r³, r⁴, and with a mutilated master gear having its teeth arranged in two vertical planes and separated thereon into quarter sections diametrically opposite to each other and adapted when the crank gears are moved on their shafts to engage the teeth of said crank gears and rotate the same, and with a series of flat faced disks carried by the shafts of said crank gears and a system of spring controlled brakes bearing upon the surface of said disks and adapted to stop the rotation of the shafts and crank gears when the said crank gears are not in mesh with the master gear, and with the shuttle boxes and a series of levers connecting the crank gears with the said shuttle boxes, all arranged, so that when said angle lever is operated by the cam d, the pattern chain is actuated and through the levers q, q', q², q³, and intermediate connections, throw the crank gears into and out of connection with the master gear, substantially as described.

GEO. GOODLINE.

Witnesses:

WILLIAM J. MCCOLLOM,
E. CLOUSTON.

55 said crank gears and rotate the same, and with the shuttle boxes and a series of levers connecting the crank gears with the said shuttle boxes, all arranged, so that when said angle lever is operated by the cam d, the pattern chain is actuated and through the levers q, q', q², q³, and intermediate connections, throw the crank gears into and out of connection with the master gear, substantially as described.

60 2. The combination of the driving shaft c, cam d carried by said shaft, angle lever e, 65 spring 37 for normally holding one arm of said lever in contact with the cam d, and means for holding lever e against the force of the spring, link g adjustably pivoted to the other arm of said lever e, with said link g, 70 pawl p', ratchet p², and sprocket wheel o carrying the pattern chain, the free end of said link g being adapted to operate said sprocket wheel o through pawl p' and ratchet p² with a series of levers q, q', q², q³, adapted to be operated by said pattern chain, a series of forked levers 75 adapted to be operated by said levers q, q', q², q³, a series of crank gears adapted to be moved on their shafts by said levers q, q', q², q³, through the series of forked levers connected to said levers q, q', q², q³, by cords r', r², r³, r⁴, and with a mutilated master gear 80 having its teeth arranged in two vertical planes and separated thereon into quarter sections diametrically opposite to each other and adapted when the crank gears are moved on their shafts to engage the teeth of said crank gears and rotate the same, and with a series of flat faced disks carried by the shafts of said crank gears and a system of spring 85 controlled brakes bearing upon the surface of said disks and adapted to stop the rotation of the shafts and crank gears when the said crank gears are not in mesh with the master gear, and with the shuttle boxes and a series of 90 levers connecting the crank gears with the said shuttle boxes, all arranged, so that when said angle lever is operated by the cam d, the pattern chain is actuated and through the levers q, q', q², q³, and intermediate connections, 100 throw the crank gears into and out of connection with the master gear, substantially as described.
